UNITED STATES PATENT OFFICE.

RUDOLPH KATOLIN, OF LOS ANGELES, CALIFORNIA.

FOLDING RULE.

Application filed July 3, 1923. Serial No. 649,193.

To all whom it may concern:

Be it known that I, RUDOLPH KATOLIN, a citizen of the United States, residing at Los Angeles, in the county of Los Angeles and State of California, have invented certain new and useful Improvements in Folding Rules, of which the following is a specification.

This invention relates to folding rules with a plurality of sections that are pivotally connected together, the object being to provide an eight inch end section with a sliding section, whereby the rule may be extended when taking in side measurements, or for measurements longer than the rule itself.

In other folding rules with which I am now familiar, the sliding section is fastened to the six inch end link or section of the rule, which is a decided disadvantage, in view of the fact that considerable time is lost when the rule is opened to take outside measurements, and in further view of the fact that the sliding section has to be pushed back a certain degree.

As it is now, the measurements will be two inches longer than the actual length of the material being measured, which will obviously occasion a loss of material.

30 A further object of my invention resides in the provision of a folding rule, wherein the same is provided with a folding end section, that is comparatively simple of construction, and will at the same time embrace the desired features of durability and efficiency.

The nature and advantages of the invention will be better understood when the following detailed description is read in connection with the accompanying drawings, the invention residing in the construction, combination, and arrangement of parts as claimed.

45 In the drawings forming part of this application, like numerals of reference indicate similar parts in the several views, and wherein:

Figure 1 is a side elevational view of a folding rule, wherein the eight inch section is provided with a sliding section.

Figure 2 is a bottom plan view thereof.

Figure 3 is a view similar to Figure 2, showing the sliding section, fully extended.

Figure 3^a is a side elevation of Figure 3.

Figures 4 and 5 are detail cross sections 55 upon the lines 4—4 and 5—5, respectively, of Figure 3^a and

Figure 6 is an enlarged perspective of the sliding section guide carried by the end of said eight inch section of the folding rule. 60

Referring to the drawings in detail, 5 designates generally a conventional type folding rule, consisting of pivotally connected sections 6, one of these sections being 8 inches in length, with the exception of the top section 6', which is of six inch length. Upon the free end of the eight inch section is an extension guide 7. This guide 7 comprises a thin oblong plate 8, formed with down turned portions 9, at the side edges 70 thereof to snugly fit within recesses upon the side edges of the said eight inch edge section of the rule. These down turned portions are formed with inwardly extending clips 10, turned against the underside of the rule section, and are formed with cutting edges 11, which enter the material of the rule section. The guide is also provided at the ends with pairs of inturned spring lugs or members 12, extending upwardly 80 from the plate at the side edges thereof to a height sufficient to permit passage or movement there over of the sliding rule section. 13 designates the sliding section that has sliding movement between the spring lugs 12 85 of the said guide 7, it being noted that the ends of this section are provided with stops 14 for limiting the sliding movement of this section in opposite directions.

In view of the above description, it will 90 at once be apparent that I have provided a folding rule, wherein the eight inch end section is provided with a sliding section for facilitating accurate measurements, this sliding section being more particularly adapted 95 for use in taking of inside measurements, or for measurements longer than the rule itself.

Although I have herein shown and described the preferred embodiment of the 100 present invention, it is nevertheless to be understood that minor changes may be made therein, without departing from the spirit and scope of the invention as claimed.

Having thus described my invention, what 105 I claim as new, and desire to secure by Letters-Patent is:

A slide rule comprising sections, stop

members mounted at the opposite ends of one section, a plate interposed between the sections, said plate being provided at its edges and at its opposite ends with inwardly disposed lugs which extend across the edges of that section having the stop members, and which are disposed between the stop mem- bers, and the said plate being provided at its stop edges and at points between the first mentioned lugs with other lugs disposed around the edges of the other rule sections. ¹⁰

In testimony whereof I affix my signature.

RUDOLPH KATOLIN.
